UNITED STATES PATENT OFFICE.

GEORGE ZINZEL, OF BATH, NEW YORK, ASSIGNOR OF ONE-HALF TO CHARLES H. MOORE, OF BATH, NEW YORK.

AUTO-LOCKING DEVICE.

1,400,928.

Specification of Letters Patent. Patented Dec. 20, 1921.

Application filed September 28, 1920. Serial No. 413,436.

To all whom it may concern:

Be it known that I, GEORGE ZINZEL, a citizen of the United States, residing at Bath, in the county of Steuben and State of New 5 York, have invented a new and useful Auto-Locking Device, of which the following is a specification.

It is the object of this invention to provide novel means whereby the lighting and 10 ignition circuits of an automobile may be maintained open, against unauthorized efforts to close the circuits and start the car.

It is within the province of the disclosure to improve generally and to enhance the 15 utility of devices of that type to which the invention appertains.

With the above and other objects in view, which will appear as the description proceeds, the invention resides in the combination 20 and arrangement of parts and in the details of construction hereinafter described and claimed, it being understood that, within the scope of what is claimed, changes in the precise embodiment of the invention 25 shown can be made without departing from the spirit of the invention.

In the accompanying drawings:—

Figure 1 shows in elevation, a device constructed in accordance with the invention; 30 Fig. 2 is a diagram illustrating the invention;

Fig. 3 is a cross section taken through the slide;

Fig. 4 is a fragmental plan showing a 35 portion of the slide.

In carrying out the invention, there is provided a support or casing 1, which, preferably, is mounted on the instrument board of a motor car. The support 1 carries a rotatable lighting switch 2 of the common sort, interposed in the lighting circuit 3. A rotatable key actuated ignition switch 4 is supplied, the switch 4 being interposed in the ignition circuit 5. The key actuated 40 switch 4 is operatively connected to an arm 6 mounted to swing parallel to the support or casing 1.

The lower end of the arm 6 is pivotally connected to an operating rod 7, the casing 50 or support 1 carrying an insulating guard 8 extended between the rod 7 and the arm 6 at the point of pivotal connection between these parts. The operating rod 7 is pivoted to one end of a first lever 9, fulcrumed intermediate its ends, as shown at 10, on the

support 1. Upward and longitudinal movement of the rod 7 is limited by a stop lug 11 carried by an insulating plate 12 mounted on the support 1. The numeral 14 marks a permutation lock, mounted on the support 60 1. A plunger 15 is mounted for right line reciprocation in the casing of the permutation lock 14, the construction being such that when a given combination is set up in the permutation lock 14, the plunger 15 can slide 65 endwise, whereas, when the predetermined combination has not been set up, the plunger 15 cannot slide endwise. The plunger is united to the first lever 9 by means of a pin and slot connection 16. 70

An insulating plate 17 is mounted on the support 1 and is provided with guides 18, between which a slide 19 is mounted for longitudinal reciprocation. The slide 19 is provided with conducting bridges 20 and 21. 75 The bridges 20 are adapted to move into and out of contact with brushes 22 on the plate 17, the bridges 21 being adapted to move into and out of contact with brushes 23 on the plate 17. Insulating strips 24 are 80 secured to the slide 19, on each side of each bridge 21—20.

The numeral 25 designates a second lever, fulcrumed intermediate its ends, as shown at 26, on the plate 17. The lever 25 is supplied at its ends with slots 27, one slot receiving a pin 28 and the operating rod 7, the other slot receiving a pin 30 and the slide 19, the operating rod 7 being cut away as indicated at 29, for the restriction of one 90 end of the lever 25.

When a predetermined combination has been set up in permutation lock 14, the plunger 15 can slide endwise, but, until such a combination has been set up, plunger 15 95 cannot slide endwise. This feature renders the entire device subject to the will of an operator, and unless the predetermined combination is known, the plunger 15 cannot slide endwise and it will be impossible to 100 close the ignition and lighting circuit. Assuming, however, that the combination has been set off and that the plunger 15 can slide endwise, the ignition switch 4 may be rotated, thereby closing the ignition circuit 105 5. The arm 6 is swung by the action of the switch 4 and longitudinal movement is imparted to the rod 7, motion being transmitted from the rod 7 to the plunger 15 by way of the lever 9. From the operat- 110

ing rod 7, motion is transmitted to the slide 19 by way of the lever 25. When the slide is moved endwise, the bridges 21 will come into contact with the brushes 23, and the 5 ignition circuit 5 will be closed completely. Similarly, when the bridges 20 come into contact with the brushes 22, the lighting circuit 3 will be closed adjacent to the slide 19, it being possible to close the lighting circuit 10 completely, and to light the car, by a manipulation of the lighting switch 2. Having thus set forth the operation of the device, it will be clear that, unless the proper combination has been set up in the 15 permutation lock 14, the plunger 15 will not be permitted to slide under the impulse originating in the ignition switch 4 and, consequently, the ignition circuit and the lighting circuit cannot be closed.

20 Having thus described the invention, what is claimed is:—

1. In a device of the class described, a pair of movable members; means for connecting said members operatively; permutation 25 mechanism controlling the movement of one of said members; a circuit; means carried by the other of said members for opening and closing the circuit; and means for operating the first specified one of said members, said means including a switch interposed in the circuit.

2. In a device of the class described, a pair of approximately parallel members mounted for longitudinal movement; means 35 carried by one of said members for opening and closing a circuit; a lever fulcrumed intermediate its ends and connected with said members; permutation mechanism controlling the movement of the other of said members; and means for operating that one of said members wherewith the permutation mechanism coacts.

3. In a device of the class described, a pair of members mounted for longitudinal movement; means carried by one of said members for opening and closing a circuit; an operating connection between said members; a permutation lock; a plunger slideable in the lock and controlled by the lock; a lever fulcrumed intermediate its ends and connected pivotally to the plunger and to the other of said members; and means for operating the other of said members.

4. In a device of the class described, a pair of members mounted for longitudinal movement; means for connecting said members; means carried by one of said members for opening and closing a circuit; a rotary switch including an arm pivoted to the other of said members; and permutation 60 means for controlling the movement of the other of said members.

5. In a device of the class described, a pair of members mounted for longitudinal movement; means carried by one of said members for opening and closing a circuit; an operative connection between said members; a rotary element having an arm pivoted to the other of said members; a lever fulcrumed intermediate its ends and connected 70 at one end to said other member; a plunger pivotally connected with the other end of the lever; and a permutation mechanism wherein the plunger slides, the permutation mechanism controlling the operation of the 75 plunger.

In testimony that I claim the foregoing as my own, I have hereto affixed my signature in the presence of two witnesses.

GEORGE ZINZEL.
